FLUID LOGIC CIRCUIT AND SHIFT REGISTER
EMPLOYING SAMEDonnie Roland Jones, Silver Spring, Md., assignor to
Bowles Engineering Corporation, Silver Spring, Md.,
a corporation of MarylandFiled Feb. 25, 1963, Ser. No. 261,180
8 Claims. (Cl. 137—81.5)

The present invention relates to pure fluid logic elements and, more particularly, to a twin and-gate for use in fluid logic systems.

The apparatus of the present invention is related to pure fluid systems of the general type described in U.S. Patent No. 3,024,805 issued to Billy M. Horton; Patent Nos. 3,001,698 and 3,016,066 issued to Raymond W. Warren and Patent Nos. 3,001,539 and 3,004,547 issued to Hyman Hurvitz.

The twin and unit of the present invention is of general applicability in pure fluid digital systems but is described in terms of its application to a pure fluid counter or shift register.

In a pure fluid counter or shift register, for purposes of discussion, as in other types of digital shift registers, it is necessary in response to a timing signal to shift information into or out of the register without losing the information as it is stepped from stage to stage therethrough. Numerous schemes have been suggested for accomplishing this result in pure fluid systems but each of the prior art devices have suffered from one or more difficulties; such as lack of sensitivity to input signals, criticality of parameters and sensitivity to environmental conditions.

It is an object of the present invention to provide a twin and gate which provides a high degree of reliability and which is relatively insensitive to environmental conditions.

It is another object of the present invention to provide a twin and unit having a high degree of sensitivity to input signals.

Still another object of the present invention is to provide a twin and unit which may be employed in pure fluid shift registers.

The above and still further objects, features and advantages of the present invention will become apparent upon consideration of the following detailed description of one specific embodiment thereof, especially when taken in conjunction with the accompanying drawings, wherein:

FIGURE 1 of the accompanying drawing illustrates the pure fluid twin and unit of the present invention; and

FIGURE 2 illustrates two fluid flip-flops interconnected by a twin and-unit to provide a shift register.

Referring specifically to FIGURE 1 of the drawings, there is provided a pure fluid device formed as channels in a plate 1 which may be of plastic, glass, or other suitable material. In use, the top surface of the plate 1, as viewed in FIGURE 1, is adapted to be covered by a further plate which forms a fluid-tight seal between the further plate and the surfaces of the plate 1 which are not recessed. In this way, fluid supplied to the apparatus is confined to the fluid paths formed as channels in the plate.

The apparatus of FIGURE 1 comprises a first nozzle 2 employed as a trigger or timing pulse input to the apparatus. The fluid is supplied to the nozzle 2 through an input aperture 3 adapted to have fluid supplied thereto at relatively precisely timed intervals. Located to the left of the nozzle 2 as viewed in FIGURE 1 of the accompanying drawing is a second nozzle 4 lying at a predetermined angle relative to the centerline of the

2

nozzle 2. The nozzle 4 is supplied with fluid through an aperture 6 and, when fluid is supplied through the aperture 6, the nozzle 4 issues fluid which intercepts fluid issued by the nozzle 2 if such fluid is being issued at that time. Positioned to the right of the nozzle 2, as viewed in FIGURE 1, is a third nozzle 7 adapted to have fluid supplied thereto through a passage 8 in the plate 1. The centerline of the nozzle 7 lies at approximately the same angle relative to the centerline of the nozzle 2 as the centerline of the nozzle 4.

In general, the fluid issued by the nozzle 2 follows a path indicated by an arrow 9; fluid issued by the nozzle 4 follows a path indicated by an arrow 11; and fluid issued by the nozzle 7 follows a path indicated by the arrow 12. The apparatus is provided, in effect, with five outlet passages. A center passage 13 is positioned downstream and along the centerline of the nozzle 2 so that fluid issued by this latter nozzle, if not intercepted by any other fluid stream, flows directly to the outlet passage 13. The passage 13 is employed as a fluid dump; that is, the fluid entering this passage may be vented directly to the atmosphere through a passage 14 formed in the plate or may be returned to the pump supplying fluid under pressure if the system is to be employed as a closed system. A further outlet passage 16 is positioned at the right side of the apparatus as viewed in FIGURE 1 and is employed to collect undeflected fluid issued by the nozzle 4. Fluid flowing to the outlet passage 16 may flow through a passage 17 in the plate 1 to the ambient atmosphere or to the return side of the pump. The passage 16 also serves to defeat boundary layer effects in that it removes sidewalls from the apparatus which might otherwise be present and which, if present, might influence the paths of flow of the various fluid streams in the apparatus. A third outlet channel or passage 18 is formed at the left side of the apparatus as viewed in FIGURE 1 and is generally a mirror image about the center line of the nozzle 2 of the outlet passage or channel 16. The passage 18 is adapted to receive an undeflected stream issued by the nozzle 7 and also serves to prevent boundary layer effects at the left side of the device.

The apparatus is provided with two further outlet passages having rather narrow inlet openings. These passages constitute signal output channels and are designated by reference numerals 19 and 21, respectively. The input orifices to the channels 19 and 21 are quite narrow so as to minimize the possibility of fluid entering these passages in the absence of fluid streams being directed precisely at their openings. This feature is not absolutely essential to the operation of the system but does impart a high degree of reliability to its operation.

In the operation of the apparatus, the input orifices 6 and 8 would normally be connected to sense the condition of some prior stage or stages of a pure fluid system. This is not an essential mode of operation of the apparatus since signals applied to these nozzles may be derived from transducers but, for purposes of explanation, it will be assumed that they receive fluid from pure fluid devices.

The system is such that, if fluid is applied initially to the nozzle 4 at a time T_1 when fluid is supplied to the nozzle 2, the fluids issued by nozzles 2 and 4 interact and the stream formed by the confluence and interaction of these two streams follows a path indicated by an arrow 22. This path is directed at the entrance to the right output passage 21 and thus, under these circumstances, fluid is supplied during the interval T_1 to this passage. During all other intervals; that is, an interval when a fluid is not supplied to the nozzle 2, fluid supplied to the nozzle 4 follows the path indicated by the arrow 11, passes through the channel 16 and is dumped. If a signal is not applied to the passage 4 at the time T_1 , then the

stream issued by the nozzle 2 enters passage 13 and is dumped. Thus, the elements comprising nozzles 2 and 4 and passages 13, 16 and 21 constitute a two-input and gate.

If, during an interval T_1 , fluid is supplied to the nozzle 7, the streams issued by nozzles 2 and 7 interact and produce a further stream having a flow path indicated by an arrow 23. This flow path is directed at the entrance of the output passage 19 and thus, when fluid is supplied to nozzles 2 and 7 concurrently, fluid is supplied to the output passage 19. If fluid is supplied only to the nozzle 7, it follows a path indicated by the arrow 12 and flows through the passage 18. Again, if fluid is issued only by the nozzle 2, it enters the passage 13 and is dumped. Thus, the device including the nozzles 2 and 7 and passages 13, 18 and 19 constitutes a second two-input and unit.

If the unit of FIGURE 1 is to be employed in a shift register, the orifices 6 and 8 are connected to two output channels 24 and 26, respectively of a single flip-flop 27. The output channels 19 and 21 are connected to two control nozzles 28 and 29, respectively of a subsequent flip-flop 31. If fluid is supplied to the nozzle 4, this indicates that the flip-flop 27 of the prior stage of the register has fluid supplied to its left output channel 24. Upon the application of a trigger or stepping impulse to the nozzle 2, fluid flows through the passage 21 to a right control nozzle 29 of the next stage of the register and causes the flip-flop to switch its flow, if it is not already so directed, to its left output channel 32 of that stage. Thus, the condition established in the stage prior to the illustrated apparatus is passed along to the stage following the illustrated apparatus.

It will be noted that, if fluid is issued by both nozzles 4 and 7 concurrently or nozzles 2, 4 and 7 concurrently, ultimate flow is along the path indicated by the channel 9. Thus, in certain applications, one or the other of the nozzles 4 and 7 may be employed as an inhibiting input to the system, further extending the utility of the device.

While I have described and illustrated one specific embodiment of my invention, it will be clear that variations of the details of construction which are specifically illustrated and described may be resorted to without departing from the true spirit and scope of the invention as defined in the appended claims.

What I claim is:

1. A pure fluid logic element having and gate characteristics comprising a first nozzle for issuing a first stream of fluid, a first outlet passage positioned downstream of said first nozzle and generally aligned with the centerline of said first nozzle, a second nozzle disposed on one side of said first nozzle and positioned to issue a second stream of fluid into intercepting relationship with said first stream of fluid, a second outlet passage positioned downstream of said second nozzle and generally aligned with the centerline of said second nozzle for receiving said second stream when undeflected, a first output passage positioned to receive a first composite stream of fluid resulting from confluence and interaction of said first and said second stream of fluid, a third nozzle disposed on the other side of said first nozzle and positioned to issue a third stream of fluid into intercepting relationship with said first stream of fluid, a third outlet passage positioned downstream of said third nozzle and disposed generally along the centerline of said third nozzle for receiving said third stream of fluid, and a second output passage positioned to receive a second composite stream of fluid resulting from confluence and interaction of said first and said third streams of fluid.

2. A pure fluid twin and unit comprising means for issuing a first stream of fluid, means for issuing a second stream of fluid into intercepting relationship with said first stream of fluid, means for issuing a third stream of fluid into intercepting relationship with the first and second streams of fluid, first output means positioned to intercept

a fourth stream of fluid formed by the confluence of said first and second streams of fluid, second output means positioned to intercept a fifth stream of fluid formed by confluence of said first and third streams of fluid, and outlet means aligned with the other of said streams of fluid and being larger than said means for issuing the other of said streams of fluid.

3. The combination according to claim 2 wherein said outlet means comprises a plurality of channels including a first channel positioned to receive said second stream of fluid when undeflected, a second channel positioned to receive said third stream of fluid when undeflected and a third channel positioned to receive said first stream of fluid when undeflected and a sixth stream of fluid formed by the confluence of said second and third streams of fluid.

4. The combination according to claim 1 further comprising a first and a second pure fluid flip-flop, each having a power nozzle, left and right control nozzles and left and right output channels, means connecting said left output channel of said first flip-flop to said second nozzle of said logic element, means connecting said right output channel of said first flip-flop to said third nozzle of said logic element, means connecting said first output passage of said logic element to said right control nozzle of said second fluid flip-flop and means connecting said second output passage of said logic element to said left control nozzle of said second flip-flop.

5. A shift register comprising a plurality of fluid flip-flops, each of said fluid flip-flops including at least a power nozzle for issuing a power stream of fluid, a pair of receiving apertures situated downstream of said power nozzle and a pair of control nozzles for issuing control streams of fluid into intercepting relation with said power stream from opposite sides thereof to deflect said power stream selectively to one and the other of said apertures, a plurality of fluid amplifiers with and gate characteristics having at least a power nozzle for issuing a power stream of fluid, a pair of receiving apertures positioned downstream of said power nozzle, and a pair of control nozzles for issuing control streams of fluid into intercepting relationship with said power stream of said amplifier from opposite sides thereof, said nozzles and said apertures of said fluid amplifier being positioned such that fluid is directed to one of said apertures only in the presence of said power stream and one of said control streams of said fluid amplifier outlet means positioned for receiving said amplifier control streams in the absence of said power stream, means connecting one fluid amplifier between each pair of fluid flip-flops with said control nozzles of said amplifier each being connected to a different one of said apertures of one of said flip-flops and each of said apertures of said amplifier being connected to a different control nozzle of another of said flip-flops and means for selectively applying fluid to said power nozzle of said amplifier to step information through said register.

6. A shift register comprising a plurality of fluid flip-flops, each of said fluid flip-flops including at least a power nozzle for issuing a power stream of fluid, a pair of receiving apertures situated downstream of said power nozzle and a pair of control nozzles for issuing control streams of fluid into intercepting relation with said power stream from opposite sides thereof to deflect said power stream selectively to one and the other of said apertures, a fluid and-gate connected between said apertures of one of said flip-flops and said control nozzles of another of said flip-flops said fluid and gate having outlet means for receiving the undeflected stream from said apertures, and means for pulsing said fluid and-gate to apply the fluid flow pattern established at the apertures of said one flip-flop to the control nozzles of the other of said flip-flops to step information through said register.

7. A shift register comprising a plurality of fluid flip-flops, each of said fluid flip-flops including at least a power nozzle for issuing a power stream of fluid, a pair

of receiving apertures situated downstream of said power nozzle and a pair of control nozzles for issuing control streams of fluid into intercepting relation with said power stream from opposite sides thereof to deflect said power stream selectively to one and the other of said apertures, fluid logic means having and gate characteristics connected between said apertures of one of said flip-flops and said control nozzles of another of said flip-flops said fluid logic element having outlet means generally aligned with said apertures for receiving the undeflected stream from said apertures, and means for pulsing said fluid logic means to apply the fluid flow pattern established at the apertures of said one flip-flop to the control nozzles of the other of said flip-flops to step information through said system.

8. The combination according to claim 1 wherein said

second and third outlet passage are positioned so as to maintain ambient pressure on opposite sides respectively of a stream of fluid issued by said first nozzle.
